US0D1086917S

(12) **United States Design Patent** (10) **Patent No.:** **US D1,086,917 S**
(45) **Date of Patent:** **** Aug. 5, 2025**

(54) **WATCH DIAL**

(71) Applicant: **OFFICINE PANERAI AG,**
Steinhausen (CH)

(72) Inventor: **Ivan Martin Martin**, Milan (IT)

(73) Assignee: **OFFICINE PANERAI AG,**
Steinhausen (CH)

(**) Term: **15 Years**

(21) Appl. No.: **29/892,515**

(22) Filed: **May 18, 2023**

Related U.S. Application Data

(62) Division of application No. 35/514,202, filed on Nov. 3, 2021 (U.S. filing date under 35 U.S.C. 384), and having an international filing date of Nov. 3, 2021, now Pat. No. Des. 1,017,442.
